CLAIM

The ornamental design for a crenellated filament package, as shown and described.

DESCRIPTION

FIG. 1 is a top plan view of a crenellated filament package, showing my new design;

FIG. 2 is an end view thereof, the undisclosed opposite end being identical;

FIG. 3 is a front elevational view thereof;

FIG. 4 is a bottom plan view thereof;

FIG. 5 is a rear elevational view thereof;

FIG. 6 is a second embodiment of the package as in FIG. 1; and,

FIG. 7 is a third embodiment of the package as in FIG. 1.

FIG. 1

FIG. 2

FIG. 3

FIG. 4

FIG. 5

FIG. 6

FIG. 7
